G. W. ALDEEN

ADJUSTABLE RANGE STOP FOR SPOTLIGHTS

Filed Nov. 6, 1924

Inventor
Gedor W. Aldeen

UNITED STATES PATENT OFFICE.

GEDOR W. ALDEEN, OF ROCKFORD, ILLINOIS, ASSIGNOR TO FYRAC MANUFACTURING CO., OF ROCKFORD, ILLINOIS, A CORPORATION OF ILLINOIS.

ADJUSTABLE RANGE STOP FOR SPOTLIGHTS.

Application filed November 6, 1924. Serial No. 748,013.

This invention relates to windshield spotlights and has more particular reference to means for limiting directional movements of the spotlight to prevent the light from being thrown in certain predetermined zones, in order to comply with the legal requirements in certain States, which laws are intended to reduce the danger and inconvenience which might result from unlimited and unrestricted 10 operation of a spotlight.

In a copending application, filed February 15, 1924, Serial No. 692,976, and now Patent No. 1,577,153, and assigned to the assignee of the present application, I have shown, described and claimed a device of a character similar to that described and claimed herein, but which is more costly to make and not as efficient as the device hereinafter described. The present invention, as distinguished from 20 the invention described in said co-pending application, is rigidly fixed to the light mechanism and in such a way that movements of the light during its use will not cause the parts to become loosened or forced out of 25 adjusted position.

The primary purpose of my invention is to provide an improved arrangement or device for limiting directional movement of a spotlight and is particularly designed for that 30 class of spotlights employing a spotlight-carrying device mounted for universal movement in a housing such, for instance, as that disclosed in the patent to Clark, No. 1,501,704, issued July 15, 1924. The invention 35 contemplates the provision of a readily attachable and detachable stop mechanism which may be adjustably positioned in the path of movement of a spotlight directional operating unit, and an arrangement whereby 40 this stop may be securely fixed in one position from which it cannot work loose.

With the foregoing and other objects in view, which will be revealed as the description of the drawing proceeds, and from the 45 claim, the invention in a preferred embodiment is illustrated in the drawing.

Fig. 1 is a vertical section through a windshield equipped with a spotlight embodying one form of my invention;

50 Fig. 2 is a section taken along the line 2—2 of Fig. 1;

Fig. 3 is an elevation of the attachment shown in Figs. 1 and 2, but removed from the spotlight; and

Fig. 4 is a sectional elevation taken along 55 the line 4—4 of Fig. 3.

The construction of the spotlight and its clamping means form the subject matter of my copending application, Serial No. 692,975, filed February 15, 1924, and assigned 60 to the assignee of the present application. This spotlight is characterized by its arrangement for universal movement in a housing in turn mounted in a windshield and clamped to opposite sides thereof above said 65 opening, and is similar to that described in the patent heretofore mentioned. There are several types of windshield spotlights of this general character that have been patented and the present invention is intended for 70 application to almost any of them.

The spotlight in the drawing generally comprises a ball 2, a stem 4 passing through or connected with the ball member, and which stem is equipped at one end with a spotlight generally designated 6 and at the other with a handle 8, for its manipulation in a housing generally designated 10, disposed through an opening indicated at 12, in a windshield glass 14. The housing 10 also includes suitable clamping means as will be evident and therefore will not be further described. The ball 2 is guided in its substantially universal movement within the housing by means of bearing members 16 and 18, the latter forming 85 part of the housing structure, and is so formed that it provides a rim 20.

The law relating to motor vehicle spotlights in some States requires that the spotlight when used on a car be so arranged that 90 it cannot be projected into an approaching pedestrian's or driver's eyes, and it is sometimes desirable to provide an arrangement whereby the light may be equipped with means that will prevent the operator 95 from projecting the light horizontally and straight ahead in front of the car to comply with the law of such States, and yet have these movement limiting means so arranged that they can be removed or 100 rendered inoperative, or adjusted to varying degrees for other States. To this end, I provide a bracket 22, having wings for lugs 24 on either side thereof, adapted to engage with the rim 20 of the housing, and this bracket 22 may preferably be bent into substantially L shape and provided at its lower end with projections 26, whereby it may

engage with and abut against the windshield glass or other rigid structure when secured to said rim 20. This construction is best illustrated in Figs. 1 and 2. The 5 rim 20 is tapped to receive one, two or more screws 28, which serve to secure the bracket to the rim and also serve to clamp an adjustable range screw 30 between the bracket and an auxiliary bracket 32, both of which 10 are formed with cooperative threads for engagement with the threads of screw 30. It will thus be apparent that when the screws 28 are loosened, the adjustable range screw 30 may be adjusted up or down in the bracket 15 set to control the range of movement of the stem 4 of the light operating means with which it contacts at certain points in the movement thereof. In its preferred form, the bracket 22 is arranged to clear one of the 20 clamping members 34, so that it does not interfere with the adjustment of such clamping member by means of slots 36 provided in its perimeter for the purpose.

With the parts in position as shown in Fig. 25 1, the stem 4 will contact with the sides of the range screw 30, preventing horizontal movement of the spotlight in a zone directly ahead, except when the reflector and other parts, designated 6, are tilted downwardly 30 to a point where the light will be thrown on engine hood of the machine, and in this position the light may be thrown from one side of the machine to the other. However, this arrangement does not prevent use of the light

in almost any desired direction when it is 35 thrown to one side of the machine, and allows a horizontal sweep of the light close to the automobile for illuminating the road bed, and full freedom of directional movement at both sides of the stop member 30 for 40 any purpose.

It will be obvious that the arrangement provided by my invention may be quickly and easily adjusted in accordance with the law, or as desired by the operator, and may 45 be applied to substantially any spotlight device by simple modification of the light or clamp. For these and other reasons, it is believed that while I have illustrated a single embodiment of the invention, it will be 50 understood that many modifications and changes may be made in the details of construction without departing from the spirit and scope of the invention as expressed in the appended claim. 55

I claim:

The combination with a spotlight having directable means, of means for limiting predetermined movements thereof comprising, a bracket adapted to be detachably connected to a substantially fixed portion of said spotlight, adjustable means on said bracket cooperative therewith and with a movable portion of said light to limit predetermined movements thereof, and means common to 60 said bracket and adjustable means to fixedly secure them. 65

GEDOR W. ALDEEN.
